UNITED STATES PATENT OFFICE.

SIGISMUND STRAUSS, OF NEW YORK, N. Y.

DESIGN FOR A TOBACCO-MOISTENER.

SPECIFICATION forming part of Design No. 33,540, dated November 13, 1900.

Application filed October 10, 1900. Serial No. 32,653. Term of patent 7 years.

To all whom it may concern:

Be it known that I, SIGISMUND STRAUSS, a citizen of the United States, and a resident of the city of New York, borough of Manhattan, 5 in the county and State of New York, have invented and produced a new and original Design for a Tobacco-Moistener, of which the following is a specification, reference being had to the accompanying drawings, forming 10 a part thereof, in which—

Figure 1 is a perspective view of a tobacco-moistener embodying the features of my design, and Fig. 2 is a horizontal section through the central portion of the moistener.

15 The leading feature of the design consists of a triangularly-shaped receptacle, the front of which is transversely curved and longitudinally tapering, while in the said front apertures appear.

20 The minor features of the design consist in upright sides 10, connecting at the back, and in a horizontal top 11; but the front edge 12

of the top 11 is convexed, and the front 13 of the device is of similar shape in cross-section and depressed gradually downward, meeting 25 the sides 10 and extending to the lower point of intersection of the sides, the front portions of the sides 10 being convexed. The front 13 of the said moistener is shown with a large aperture and with surrounding smaller apertures.

Having thus described my invention, I claim as new and desire to secure by Letters Patent—

The design for a tobacco-moistener herein 35 shown and described.

In testimony whereof I have signed my name to this specification in the presence of two subscribing witnesses.

SIGISMUND STRAUSS.
